No. 36,651.

Patented December 1, 1903.

UNITED STATES PATENT OFFICE.

HENRY WEBER, OF NEW YORK, N. Y.

DESIGN FOR A SPOUT FOR SILVERWARE OR SIMILAR ARTICLES.

SPECIFICATION forming part of Design No. 36,651, dated December 1, 1903.

Application filed November 3, 1903. Serial No. 179,750. Term of patent 3½ years.

To all whom it may concern:

Be it known that I, HENRY WEBER, a citizen of the United States, residing at No. 188 South Oxford street, borough of Brooklyn, city of New York, in the county of Kings and State of New York, have invented a new, original, and ornamental Design for a Spout for Silverware or Similar Articles, of which the following is a specification, reference being had to the accompanying drawings, forming part thereof.

Figure 1 of the drawings shows a side elevation of my design, and Fig. 2 shows a front elevation.

What I claim as new, and desire to secure 15 by design Letters Patent, is—

The ornamental design for a spout for silverware or similar articles substantially as shown.

In testimony whereof I have signed my 20 name to this specification in the presence of two subscribing witnesses.

HENRY WEBER.
